DESIGN FOR A RETINOSCOPE

John R. Miles, Ann Arbor, Mich.

Application December 2, 1939, Serial No. 88,642

Term of patent 7 years

To all whom it may concern:

Be it known that I, John R. Miles, a citizen of the United States and a resident of Ann Arbor, county of Washtenaw and State of Michigan, have invented a new, original, and ornamental Design for a Retinoscope, of which the following is a specification, reference being had to the accompanying drawing, forming a part thereof.

Fig. 1 is a rear elevation of a retinoscope embodying my design.

Fig. 2 is a side elevation of the retinoscope head.

Fig. 3 is a front elevation of the retinoscope head.

Fig. 4 is a top plan view of the retinoscope head. The characteristic features of my design are shown in full lines.

I claim:

The ornamental design for a retinoscope, substantially as shown, and described.

JOHN R. MILES.
